UNITED STATES PATENT OFFICE.

GEORGE MULLER, OF NEW YORK, N. Y., ASSIGNOR TO THE SETH THOMAS CLOCK COMPANY, OF THOMASTON, CONN.

DESIGN FOR CLOCK-CASE.

Specification forming part of Design No. **11,105**, dated September 9, 1879; application filed August 14, 1879.
[Term of patent 3½ years.]

To all whom it may concern:

Be it known that I, GEORGE MULLER, of New York city, in the State of New York, have originated and designed a Style or Pattern for Clock-Cases, of which the following is a full, clear, and exact description, reference being had to the accompanying photographic illustrations, making part of this specification.

Figure 1 is a face (slightly in perspective) view, and Fig. 2 is a side or edge view.

Similar letters of reference indicate like parts in both the illustrations.

The body of the clock-case is in the form of a cylinder, having a length considerably less than its diameter, as indicated by A. At each end the diameter is a little greater for a length about quarter the length of the whole. These enlarged parts are marked A'. They correspond to the rings or hoops at the ends of a bass-drum, and the entire form and proportions correspond closely therewith. It looks like a miniature bass-drum wrought in handsome metal-work, one face of the drum being utilized as the clock-face, and equipped with figures, hands, &c., therefor, and the other face or end of the drum being utilized for the back of the clock, and necessarily differing from a drum in having the necessary appurtenances therefor. The back face is sunk, however, about the same as the end of a drum.

I further cause the design to partake of the character of a drum by applying parts B in imitation of drum-ropes. They present the appearance of bright and attractive drum-ropes extending around pins b, set in or attached to the hoops B, and tightened by slides

C, presenting the appearance of the corresponding parts on a drum. These parts may, like the rest, be of burnished metal, or any other material adapted to serve as a clock-case.

D D D D are spheroidal legs, attached at the points indicated. They mark the lower side of the clock, and cause it to differ from the complete appearance of a drum, even in side view, but without destroying the general drum-like effect. They constitute a feature or set of features added to the general imitation of a drum.

E is a ring, which is set or attached at the upper and back edge.

Both the part E and the parts D may be omitted, or one part, E, alone, or the parts D alone, may be omitted, without departing from the main feature of the design.

What I claim as my design is—

1. The clock-case design having the cylindrical body A, hoops A' A', drum-rope B, pins or holds b, and slides C, presenting the effect of a drum in its general contour, with a clock-face at one of its ends, as herein specified and shown.

2. The clock-case design presenting the general effect of a drum, with a clock-face as one of its ends, and having in addition the spheroidal attachments D D D D, as herein set forth and described.

GEORGE MULLER.
